UNITED STATES PATENT OFFICE.

ALBERT F. JOHNSTON, OF FORD CITY, PENNSYLVANIA, ASSIGNOR TO PITTSBURGH PLATE GLASS COMPANY, OF FORD CITY, PENNSYLVANIA, A CORPORATION.

RUNNER FOR GRINDING CURVED-GLASS SURFACES.

Application filed December 13, 1920, Serial No. 430,141. Renewed February 6, 1924.

To all whom it may concern:

Be it known that I, ALBERT F. JOHNSTON, a citizen of the United States, residing at Ford City, in the county of Armstrong and State of Pennsylvania, have invented certain new and useful Improvements in Runners for Grinding Curved-Glass Surfaces, of which the following is a specification.

The invention relates to grinding runners designed for use in grinding, smoothing or polishing curved surfaces such as the inner and outer surfaces of glass blanks for use as parabolic mirrors. It has for its principal objects the provision of an improved runner which will adapt itself to the general curvature of the surface to be ground and produce a finished surface which accurately follows the desired curvature; which applies yielding, substitutionally uniform pressure, throughout the working area of contact between the runner and the glass; and which is of cheap, simple construction and requires a minimum amount of skill in use. Certain embodiments of the invention are illustrated in the accompanying drawings, wherein:

Figure 1 is a vertical section showing the improved runner in position of use for grinding a convex surface. Figure 2 is a plan view of the bottom of the runner. Figure 3 is an enlarged section through a part of the runner and the table upon which it is mounted. Figure 4 is a plan view of the top of the runner. Figure 5 is a partial vertical section through a runner modified in construction for grinding a concave surface, and Figure 6 is a partial vertical section through the edge of the runner and table when the runner is employed for polishing.

In its preferred form the runner comprises a disc of felt or other flexible material which is unsupported except in its central portion where the spindle is attached, the intent being to leave the outer portion of the felt sheet free so that it can adapt itself to the contour of the surface being ground. The front face of the sheet or disc is provided with metal grinding members, preferably in the form of screws or nails having their shanks embedded in the felt and having their heads exposed so as to act as grinding elements. These grinding elements are preferably arranged around the periphery of the disc, the central portion of the

disc not being provided with any grinding means. When the runner is used for polishing, the metal grinding elements are, of course, omitted, rouge or other polishing material being employed as in ordinary polishing operations.

The general movements of the runner are similar to those which have already been used in the art with other types of runners, the runner having its spindle carried around in a circle approximately concentric with the center of rotation of the table carrying the article to be ground but in a direction which is the reverse of the direction of rotation of the table. The runner itself is preferably left free to rotate with respect to its spindle and its diameter is preferably such that it overlaps the edge of the table on one side and the center of the rotation of the table on the other side.

Figure 1 illustrates in a somewhat diagrammatic form the application of the runner in grinding a convex surface. In this construction 1 is the table carrying the glass blank 2 and rotated from the shaft 3; 4 is a felt sheet constituting the full member of the runner; 5 is a metal plate by means of which the felt sheet is connected to its spindle; 6 is the spindle mounted upon the arm 7; 8 is the shaft by means of which the arm 7 is rotated; and 9 is the bearing for the shaft 8, such bearing being carried adjustably in the frame comprising the channel bars 10.

The plate 5 has a universal connection 90 with the spindle 6 as indicated at 11, so that the runner can adjust itself to the glass and the arm 7 is adjustable transversely in the fork 12 carried by the lower end of the shaft 8 so that the runner can be adjusted radially 95 as desired, an adjusting nut 13 serving to clamp the arm 7 in any adjusting position.

The lower face of the runner is provided with grinding elements in the form of the headed studs 14 screwed into the felt sheet 4 as indicated in Figure 3. These studs are preferably arranged in a staggered relation as indicated in Figure 2, but this is not necessary, a large number of various arrangements being possible. As indicated 105 in Figure 1, the outer edge of the runner overlaps the outer edge of the table so that the inner row of grinding elements comes opposite the edge of the table. At its opposite edge the runner overlaps the central 110

line of the table so that the inner row of grinding elements cuts through the center line of the table. The central portion of the felt sheet 4 does not touch the glass bearing spaced away therefrom by the felt blocks 15, shown in Figure 2, such blocks being secured to the face of sheet 4 by screws or nails. The plate 5 is secured to the felt sheet by means of the bolts 16. The felt blocks 15 prevent the bolt heads from touching the glass.

In order to provide for the necessary pressure to give a proper grinding action, a plurality of weights 17, preferably arranged as indicated in Figure 4 are employed. These weights are separated and independent so as to permit the felt sheet to adjust itself to the glass and various arrangements of these weights might be made depending upon conditions. Experience has indicated, however, that the best arrangement involves the placing of these weights close to the periphery of the sheet as indicated. The stiffness of the sheet of felt is such that the pressure of these weights is not localized and a uniform grinding action is secured over the entire area covered by the grinding elements. In order to prevent the felt from becoming water-soaked, a sheet of rubber 18 may be employed upon the face of the felt as indicated at Figure 3, and the back of the felt may be covered with a stiffening coating of pitch 19 which protects the felt and confines the flexibility more or less to the outer portion of the felt sheet.

In operating the device, a coarse abrasive is first used, as in ordinary grinding operation, followed by finer and finer abrasive, ending up with fine grades of emery. This is followed by a polishing operation in which a runner similar to the runner 4, but without the grinding elements, is employed.

Figure 5 illustrates a modification in which the concave side of the glass sheet 20 is to be ground upon the table 21, the felt sheet 22 being curved to conform with the curve of the glass and being supported by the plate 23 and provided with the grinding elements 24, the construction aside from the reversal of curvature, being similar to that heretofore described. The weights 25 are arranged around the periphery just as in the other construction.

Figure 6 illustrates the use of the runner 26 without any grinding elements, this construction being employed for polishing. The glass 27 is supported upon the table 1 and rouge is employed in place of the abrasive. The weights 28 correspond to the weights 17 as used in the construction of Figure 1. Throughout the grinding and polishing operations the runners may be shifted or adjusted from time to time to

meet requirements and the arrangement and distribution of the grinding elements and weights may be modified to suit conditions.

What I claim is:

1. In combination, a runner for use upon a curved surface, comprising a spindle, and a weighted flexible member carried thereby adapted to conform itself to the curved surface.

2. In combination, a runner for use upon a convex surface, comprising a spindle, and a flexible member having a concave face carried thereby adapted to conform itself to the curved surface, and a plurality of devices for applying pressure at separated points upon the back of said member, the said member having sufficient body to prevent the pressure from being localized whereby a uniform pressure is exerted by the face of the member.

3. In combination, a runner for use upon a curved surface, comprising a spindle, and a flexible member carried thereby adapted to conform itself to the curved surface, and a plurality of weights distributed over the rear face of said member.

4. In combination, a runner for use upon a curved surface, comprising a spindle, a face member carried thereby consisting of a sheet of felt unsupported at its outer portion, adapted to conform itself to the curved surface and means for applying pressure upon the unsupported portion of said member.

5. In combination, a runner for grinding a curved surface comprising a spindle, a flexible face member carried thereby and having its outer portion unsupported and comprising a sheet of felt adapted to conform itself to the curved surface, a plurality of weights distributed over the rear side of the felt, and metal grinding members secured upon the front of said sheet.

6. In combination, a runner for grinding a curved surface comprising a spindle, a flexible face member carried thereby and having its outer portion unsupported and comprising a sheet of felt adapted to conform itself to the curved surface, a plurality of weights distributed over the rear side of the felt, and metal grinding members secured upon the front of said sheet, and comprising headed members with shanks projecting into the sheet.

7. In combination in a grinding and polishing device, a runner disc having its central portion comparatively rigid and its periphery flexible to permit it to adapt itself to the surface of the glass and a plurality of weights arranged upon the rear side of the peripheral portion of the disc.

Signed this 30 day of Nov. 1920.

A. F. JOHNSTON.
